UNITED STATES PATENT OFFICE.

HAROLD K. PARSONS, OF SOUTHBRIDGE, MASSACHUSETTS.

EYEGLASSES.

1,119,035.

Specification of Letters Patent.

Patented Dec. 1, 1914.

Application filed March 28, 1913. Serial No. 757,376.

To all whom it may concern:

Be it known that I, HAROLD K. PARSONS, a citizen of the United States, residing at Southbridge, in the county of Worcester and State of Massachusetts, have invented certain new and useful Improvements in Eyeglasses, of which the following is a specification.

My invention relates to improvements in eyeglasses and has particular reference to that type in which pivoted spring pressed guards are employed for retaining the mounting in position on the face of the wearer.

15 The leading object of my invention is the provision of improved means for detachably securing the actuating spring for the said guards.

A further object of my invention is the provision of a new, attractive and readily constructed and assembled mounting.

Other objects and advantages of my improved construction should be readily apparent by reference to the following description taken in connection with the accompanying drawings and it will be understood that I may make any modifications in the specific details of construction shown and described within the scope of the appended 30 claims without departing from or exceeding the spirit of my invention.

Figure I represents a front view of a pair of eyeglasses embodying one form of my improvement. Fig. II represents a bottom plan view thereof. Fig. III represents a section view on the line III—III of Fig. II. Fig. IV represents a plan view of a slightly modified construction. Fig. V represents a sectional view on the line V—V of Fig. IV. Fig. VI represents a detail view of another modification. Fig. VII represents a plan view of a blank for constructing one of the forms of my invention. Fig. VIII represents a sectional view illustrating a mounting embodying the blank shown in Fig. VII. Fig. IX represents a sectional view of another modification. Fig. X represents a bottom plan view of the construction shown in Fig. IX. Fig. XI represents a fragmentary sectional view in which the parts are located on the forward side of the bridge. Fig. XII represents a sectional view of a further modification of my invention. Fig.

XIII represents a bottom plan view of the construction shown in Fig. XII.

55

In the drawings, in which similar characters of reference are employed to denote corresponding parts throughout the various views, the numeral 1 designates the lenses secured between the clip ears 2 of the lens 60 clip which has the strap portion 3 to which is attached the bridge 4 in the usual manner.

In that form of my invention illustrated in Figs. I to III inclusive I have illustrated the lever arm 5 as pivotally mounted on the under side of the bridge 4, being secured in position by the pivot 6, but it will be understood that in this form as in the other forms of my invention the lever arm and spring may be located on either the under 70 or upper side of the bridge, Fig. XI illustrating a reversal of one of the constructions, namely that shown in Figs. I, II and III. The guard arm 5 bears on one end the guard 7 of any suitable construction and 75 is preferably provided on the opposite end with a finger piece 8 for ready operation of the guard lever. Formed on one side of the lever adjacent the pivot aperture is a lug or finger 9 adapted to be bent downwardly 80 and have the terminal portion 10 thereof extending outwardly to form a slight shoulder. Resting upon this shoulder is the inner end of the spring 11 which is formed with a hook 12 for engaging the finger 9, the 85 shoulder supporting the spring holding the same in place, the outer end bearing against the strap 3 of the mounting. To remove the spring it is merely necessary to disengage the hook 12 from the finger and then laterally shift the spring until it is out of engagement with the shoulder 10, when it may be quickly slipped off.

In Figs. IV and V, I have illustrated a slight modification of my construction in 95 which the lever 5 spans the bridge 4 and the finger 9 is the terminal of the portion of the material instead of being bent down from one side thereof, said finger being provided with the shoulder retainer 10 and the 100 spring having the hook 12 for engaging the finger.

In Fig. VI, I have shown another slight modification in which the pivot 13 is integrally secured to the lever and adapted to 105 pass freely downward through the bridge,

said pivot being provided with a slot 14 and shoulders 15 whereby the spring may be engaged in the slot and under tension will rest on the shoulders 15 which hold it under ordinary conditions against accidental disengagement.

In that form of my invention illustrated in Fig. VII, I have shown the lever arm 5 as provided with two fingers 9 extending from opposite sides, either of these fingers being adapted to lie parallel to each other as shown in Fig. VIII, whereby two portions of the spring instead of one are supported by the shoulders 10.

In that form of my invention shown in Fig. IX in place of the finger 9 extending downwardly entirely through the spring and shoulder portion being disposed on the under side of the spring, I form on the inner 15 end of the spring an aperture 16 which receives the bent or shoulder portion 10 of the finger, while to further support the spring I form on the outer end the offset portion 17 adapted to be bent to lie under the coils of the spring and having a notch 18 formed in the terminus thereof to fit around the strap 3 and lock the outer end of the spring against rotation, the strap being provided with a lug 19 fitting beneath the portion 17 of the 20 spring to support the same. The form of my invention shown in Fig. XI requires no particular description inasmuch as this form illustrates the same construction as that shown in Figs. I, II and III, with the exception that the spring and lever have been placed on the upper instead of the under side of the mounting.

In that form of the invention shown in Figs. XII and XIII in place of forming the finger 9 with a shoulder I so dispose the lug 19 on the strap 3 that it will fit into the aperture 20 formed in the outer portion of the spring, the lug thus supporting the spring while the spring is provided on its inner end 45 with the inwardly bent notched or apertured portion 17, the notch or aperture 18 thereof engaging the finger 9 and frictionally resisting downward movement of the spring to supplement the action of the lug 19 in supporting the said spring.

From the foregoing description taken in connection with the accompanying drawings, the construction of my improved mountings should be readily apparent and it will be seen that I have provided a construction embodying as its essential feature a pivoted guard arm having a depending finger portion for engaging the inner end of the spring in such manner that the spring may be readily detached therefrom when desired for removal and replacement without the position of the guard being disturbed, and in which when the spring is in position the inner end of the spring will move upon piv-

otal movement of the guard to wind the 65 spring while uncoiling of the spring will tend to shift the guard into gripping position.

While in the majority of forms of my invention illustrated, I have shown what is 70 commonly termed a flat spring, it will be understood that most of the forms shown are adapted for use with either flat, half round or round springs, although same are particularly adapted for use with the flat 75 springs, and it is for that reason that I have illustrated my mounting as equipped with flat springs.

I claim:

1. The combination with a pivoted lever 80 having a projection thereon adjacent but out of axial alignment with its point of pivotance, of a spring removably mounted on said projection and having its inner end interlocked therewith.

2. The combination with a support and a lever pivoted thereto, of a spring on the same side of the support as the lever adapted to actuate the lever, and means to one side of the turning axis of the lever for engaging 90 the inner end of the spring.

3. The combination with a support and a lever turning thereon, of a spring substantially axial with the turning axis of the lever for actuating the lever and means carried by the lever and disposed to one side of the turning axis for engaging the inner end 95 of the spring.

4. In an eyeglass mounting, the combination with the bridge, of a guard arm mounted to turn thereon about a substantially vertical axis, a spring for actuating the guard arm coiled around said axis and to one side of the bridge and arm, a finger projecting at one side of but parallel to the turning axis 105 of the lever and within the coils of the spring, and a shoulder for preventing relative axial movement of the spring and other parts.

5. As an article of manufacture, a blank 110 for a nose guard arm comprising a strip of material, having a handle at one end and a bearing portion at the opposite end thereof, said strip having a pivot aperture formed therein intermediate the length thereof, and having a finger immediately adjacent said pivot aperture adapted to be bent parallel to the axis of the lever to engage the inner end 115 of the spring.

6. In an ophthalmic mounting, the combination with a support, of a pivot carried 120 thereby, a lever mounted on the pivot and having a finger integral therewith and projecting therefrom parallel to the pivot axis and to one side of said axis, and an actuating 125 spring for the lever coiled in a flat spiral having one end engaging the support and the opposite end interlocking with the fin-

ger, the finger having a portion for engaging the spring to secure the same in position, and the position of the finger being such as to describe an arch winding up the spring 5 without binding upon pivotal movement of the lever in one direction.

In testimony whereof I affix my signature in presence of two witnesses.

HAROLD K. PARSONS.
